FAUCET SPOUT

Henry Bruewer, Cincinnati, Ohio, assignor to The
Schaible Company, Cincinnati, Ohio, a corpora-
tion of Ohio

Application February 26, 1948, Serial No. 11,170

7 Claims. (Cl. 137—111)

1

This invention relates to plumbing fixtures and more particularly relates to a faucet spout of improved construction and to a method of making a faucet spout.

Faucet spouts in the past have been fabricated from castings or bent pipes which have required considerable machining to form and complete, and it has been a principal object of the present invention to provide an improved faucet spout fabricated from sheet metal parts.

Conventional faucets of cast metal have a rough finish requiring grinding and other finishing operations to eliminate roughness, and, in addition, rough castings often have hidden flaws which only become evident after considerable effort has been expended on a piece which must thereafter be discarded. Therefore, it has been a further object of this invention to provide a sheet metal faucet spout having smooth surfaces which require a minimum of machining.

A further object of this invention has been to provide a firm juncture between a tubular pipe fitting and a sheet metal faucet spout.

The above and other objects are attained by the means set out in the accompanying drawing, in which:

Figure 1 is a perspective view showing a faucet spout constructed in accordance with this invention.

Figure 2 is an enlarged sectional view along line 2—2 in Figure 1 showing the faucet spout prior to heating to solder the parts together.

Figure 3 is an exploded view showing the parts used to fabricate the faucet spout.

Figure 4 is a sectional view along line 4—4 in Figure 1 showing the faucet spout in completed form with the parts soldered together.

Briefly, the faucet spout of this invention may include a pair of hollow sheet metal sections soldered or brazed together to form a hollow body. One section may be slightly smaller than the other so that it can be pressed or otherwise closely fitted inside a peripheral edge of the other. The first mentioned section may be equipped with a peripheral channel facing the peripheral edge of the other section when in assembled relation in which channel a strip or wire of appropriate hard solder may be held. The sections may be permanently and tightly joined together by heating to melt the strip or wire of solder so that it fills and seals a circumferential opening between the edges of the sections. One of the sections may be equipped with circular openings at either end to receive fittings for channelling water, or other liquid, into and out of the hollow body. Fittings may be soldered into

2

the openings either at the time the sections of the body are soldered together or in a separate operation.

As shown in the drawing, the faucet spout may include a body 10 constructed from an elongated hollow upper section 11 and an elongated hollow lower section 12 which fit together, the lower section fitting inside a downwardly extending peripheral wall 13 of the upper section 11. The lower section 12, as shown, may have an upwardly extending peripheral wall 14 which extends upwardly inside the wall 13. As shown in Figures 2 and 3, the wall may be bent inwardly adjacent a lower surface 16 of the section 12 to form a peripheral channel 17 between the wall 13 and the wall 14. A wire 18 of suitable hard solder may be fitted into the channel 17 before the sections 11 and 12 are assembled. A series of lugs 19 spaced along the free edge 20 of the wall 14 and formed by outwardly bent sections of the edge 20 may hold the wire 18 in place so that it cannot slip from the channel 17 during assembly of the faucet spout.

The surface 16 may be equipped with spaced circular openings 21 and 22 at opposite ends for receiving a water intake 23 and outlet 24. The water intake 23 may be a tubular member having circumferential slots 26 in its walls for rotatably attaching the faucet spout to other plumbing fixtures. A shoulder 27 near one end of the intake 23 may rest against a washer 28 which fits between the surface 16 and the shoulder 27. A tip 29 of the intake 23 may fit through the center of the washer 28 and through the opening 21 forming a close fit to receive solder. A ring 30 of solder may be fitted about the washer 28 when the faucet spout is assembled and, upon heating, it has been found that solder from the ring 30 can penetrate between the washer 28 and the surface 16 to the tip 29 to form a tight bond between the tip 29, washer 28, and opening 21, which is completely water tight. The intake 23 may be mounted on the slots 26 on conventional fixtures, not shown, and the soldered joint between the inlet 23 and the body 10 may be sufficiently strong to withstand the shocks incident to rotation and use of the faucet spout.

The outlet 24 may include a tip 32 which can fit inside the opening 22 and an enlarged lower end 33 which may be threaded, as shown, to receive fixtures served by the faucet spout. Intermediate the tip 32 and the threaded end 33, a shoulder 34 may be located which may serve to receive a ring 36 of solder and provide a surface 37 abutting the lower surface 16 of the lower

section 14 to provide an interface for forming a tight soldered joint.

The faucet spout may be assembled conveniently in inverted position. The upper section 11 may be placed with its peripheral wall 13 directed upwards. The wire 18 may be placed in the channel 17 of the section 12 and the wall 14 of the section 12 fitted inside the wall 13. The section 12 may be pressed against the section 11 until the surface 12 is flush with the free edge of the wall 13 as shown in Figure 2. The intake 23 and outlet 24 may be set in the openings 21 and 22 in proper assembled relation with the solder rings 30 and 36 and the washer 28. Then the entire faucet spout may be heated to form all the soldered joints in a single operation. The construction of the channel 17 and the lugs 19 prevents the wire 18 from falling into the hollow space between the sections, and, when the faucet is heated, the solder of the wire 18 melts and creeps into the peripheral crack between the sections to form a water-tight peripheral joint. At the same time the solder of the rings 30 and 36 joins the intake and outlet, respectively, to the openings 21 and 22. The solder forms water-tight junctures between the parts. As shown in Figure 4, solder from the wire 18 flows to form a circumferential juncture 39 joining the upper section 11 and the lower section 12. Solder from the ring 30 may flow to form a juncture 41 which joins the intake 23, washer 28, and opening 21 to form a firm water-tight connection. In a similar manner, solder from the ring 36 forms a juncture between the outlet 24 and the opening 22.

The faucet spout of this invention may be fabricated completely from sheet metal and turned parts requiring neither castings nor bent pipe. The upper and lower sections 11 and 12 may be formed from sheet metal and may easily and simply be formed in a drawing operation. The body 10, formed from the sections 11 and 12, may be of any appropriate shape. It is here shown tapering from the intake 23 to the outlet 24, but the shape of the body need not be limited to shapes which can be formed from bent pipe but may be formed in any desired decorative shape. The surface roughness and possibility of surface and hidden imperfections found in castings is eliminated by the use of sheet metal, for sheet metal surfaces may be smooth so that any imperfections may be immediately apparent without need for extensive machining to bring them out. Further, if it is desired to plate the surface of the faucet spout with chromium or other metal, the smooth sheet metal surfaces can be quickly and conveniently prepared for plating without the necessity for preliminary machining to eliminate surface imperfections resulting from casting. Moreover, the interior surfaces of the body 10 may be smooth, unlike the interior surfaces of a casting, and there may be less resistance to the flow of water through a faucet spout constructed in accordance with this invention than is found in a cast faucet spout of equivalent size.

It is to be understood that the parts may be joined together with various types of solder or may be brazed together. Various metals may be used in the fabrication of the faucet spout and various modifications in structural details may be resorted to within the scope of the appended claims without departing from the spirit of the invention.

Having described my invention, I claim:

1. A faucet spout which comprises a pair of hollow elongated trough-shaped metal sections each having closed ends and an open side, one of said sections being inverted and disposed within the peripheral edge of the open side of the other section, the peripheral edge of the inner section containing an outwardly facing peripheral channel adapted to hold a solder wire during fabrication of the faucet spout, a soldered, liquid-tight juncture between said peripheral edges to form an enclosed chamber between said sections, one of said sections containing a pair of spaced openings, and an intake fixture soldered to one of said openings for introducing liquid into the chamber, the other opening being an outlet opening for discharge of liquid from the chamber.
2. A faucet spout which comprises a pair of hollow elongated trough-shaped metal sections each having closed ends and an open side, one of said sections being inverted and disposed within the peripheral edge of the open side of the other section, the peripheral edge of the inner section containing an outwardly facing peripheral channel adapted to hold a solder wire during fabrication of the faucet spout, a soldered, liquid-tight juncture between said peripheral edges to form an elongated enclosed chamber between said sections, one of said sections containing a pair of spaced openings adjacent opposite ends of said chamber, and an intake fixture soldered to one of said openings for introducing liquid into the chamber, said intake fixture being mounted substantially perpendicular to said elongated chamber and being adapted to rotate about a vertical axis to permit the chamber to rotate in a horizontal plane, and an outlet fixture soldered to the other opening to permit liquid to leave the chamber.
3. A faucet spout which comprises a pair of hollow elongated trough-shaped metal sections each having closed ends and an open side, one of said sections being inverted and disposed within the peripheral edge of the open side of the other section, the peripheral edge of the inner section containing an outwardly facing peripheral channel for receiving a solder wire during fabrication of the faucet spout, lugs spaced about said edge, said lugs being inclined outwardly to hold the solder wire in said channel, a soldered, liquid-tight juncture between said peripheral edges to form an enclosed chamber between said sections, one of said sections containing a pair of spaced openings adjacent opposite ends of said chamber, an intake fixture attached to one of said openings, and an annular disc between said intake fixture and said opening, said intake fixture having a shoulder abutting said disc and a tip extending through said disc into said opening, said intake fixture and disc being soldered together and to the opening.
4. A faucet spout which comprises a pair of hollow elongated trough-shaped metal sections each having closed ends and an open side, one of said sections being inverted and disposed within the periphery of the open side of the other section, and a soldered liquid-tight juncture between sides and ends of said sections to form a fluid-tight chamber within said sections, said sections having an inlet and an outlet adjacent the respective ends thereof.
5. A faucet spout which comprises a pair of hollow elongated trough-shaped metal sections each having closed ends and an open side, one

of said sections being mounted within the other section with its open side within said section, the side and end walls of said sections being substantially in contact, the walls of the section within the other section containing an outwardly facing channel for receiving a solder wire during fabrication of the faucet spout, there being a liquid-tight juncture of fusible metal between said sections whereby a fluid-tight chamber is formed between said sections, one of said sections having in the wall opposite its open side a pair of spaced openings adjacent the respective ends of the spout, and means for connecting one of said openings to an inlet swivel fixture for introducing liquid into the spout, the other opening being an outlet for discharging liquid from the spout.

6. In combination, a pair of hollow elongated trough-shaped metal sections each having closed ends and an open side, one of the said sections being inverted and being substantially co-extensive with and disposed within the open side of the other section, said sections having side and end walls substantially in contact, the walls of the inner section containing an outwardly facing channel, and a solder wire in said channel embracing the walls of the inner section, the solder of the solder wire being adapted to flow between the walls of the sections when the sections are heated to a temperature at which the solder fuses.

7. In combination, a pair of hollow elongated trough-shaped metal sections each having closed

ends and an open side, one of said sections being inverted and being substantially co-extensive with and disposed within the open side of the other section, said sections having side and end walls substantially in contact, the walls of the inner section containing an outwardly facing channel, and a solder wire in said channel embracing the walls of the inner section, one of said sections having a pair of spaced openings in a wall opposite its open side adjacent the respective ends of the section, the solder of the solder wire being adapted to flow between the walls of the sections when the sections are heated to a temperature at which the solder fuses.
